UNITED STATES PATENT OFFICE.

HARRY J. DURBOROW, OF PHILADELPHIA, PENNSYLVANIA.

STYLUS-BAR MOUNTING FOR SOUND BOXES.

Application filed December 16, 1920. Serial No. 431,063.

To all whom it may concern:

Be it known that I, HARRY J. DURBOROW, a citizen of the United States, residing at Philadelphia, in the county of Philadelphia and State of Pennsylvania, have invented 5 certain new and useful Improvements in Stylus-Bar Mountings for Sound Boxes, of which the following is a specification.

One object of my invention is to provide a 10 mounting for a stylus bar for sound boxes of talking machines which will effect an improved or more accurate reproduction of sound.

Another object is to make such mounting 15 of a construction which can be quickly and easily installed.

A further object is to make my improved 20 mounting of a durable construction and so that it can be quickly and easily manufactured.

These objects, and other advantageous 25 ends which will be described hereinafter, I attain in the following manner, reference being had to the accompanying drawings in which—

Figure 1 is a front elevation of a sound box including my improved stylus bar mounting,

Figure 2 is an inverted plan view of Figure 1,

Figure 3 is an enlarged fragmentary section taken on the line 3—3 of Figure 1,

Figure 4 is an enlarged fragmentary sectional elevation taken on the line 4—4 of Figure 2,

Figure 5 is an enlarged front elevation of a spring device which forms a part of my invention,

Figure 6 is a bottom plan view of the device shown in Figure 5,

Figure 7 is a top plan view of the device shown in Figures 5 and 6, and

Figure 8 is a plan view of a blank out of which the device shown in Figures 5, 6 and 45 7 is constructed.

Referring to the drawings, 9 represents a sound box including a diaphragm 10; the frame 11 of said box having a projection 12 providing two lips 13 which are spaced 50 apart and extend downwardly to provide an intervening space 14. A stylus bar 15 has its upper end secured to the diaphragm and at its lower end is provided with a needle chuck 16; said needle chuck having a flat upper surface 17 which is located to the rear

of the stem portion 18 of the stylus bar which connects with the diaphragm 10.

My invention includes a device 19 which is made from a blank of sheet material, for example from bronze or spring steel; said blank including a central portion 20 having integrally formed strips 21 and 22 which extend in opposite directions and at a slant to the portion 20 as clearly shown in Figure 8. The strips 21 and 22 while in the blank may 60 be made substantially parallel to each other or in other words are included in parallel planes. These strip portions 21 and 22 are turned or twisted into a helical form such for example as clearly shown in Figures 5 65 to 7 inclusive and each of the strips 21 and 22 at their free ends have an enlarged flat portion 23. These portions 23 are so arranged, that after the strip portions 21 and 22 are twisted in helical form, that they will 70 be in a straight line with the central portion 20 and in the same plane therewith. Figure 5 shows these portions 23 in the same plane with the portion 20 and Figures 6 and 7 show that these portions 23 are in straight 75 alignment with the portion 20. Thus my improved device is in the form of a helical spring having opposite end portions flat and a central flat portion as clearly obvious from the construction illustrated in the drawing. 80

The central portion 20 is preferably provided with two holes 24 and the end portions 23 are preferably provided with a hole 25. Screws 26 extend through the holes 24 and secure the portion 20 to the surface 17 of the 85 needle chuck 16. While other screws 27 secure the end portions 23 to the under surfaces of the lips 13 and in this manner the stylus bar is resiliently connected to the frame of the sound box, I may in some instances insert cores 28 within the turns or helical portions 29 of the device 19 and these cores as illustrated are made of cork and serve to kill or stop any vibrations imparted to the device which might otherwise tend to 90 deflect sound directly from the device instead of transmitting the vibrations through the stem 18 of the stylus bar to the diaphragm 10.

A stylus bar mounting such as above described, can be quickly and easily made and installed and has been found to give exceptionally good results. A mounting is provided thereby which permits a firm connection but a resilient connection since the de- 105 110

vice can permit a certain yielding movement of the stylus bar in either direction within the length of the device and also a torsional or turning movement which serves 5 to keep the parts central during use.

While I have described my invention as taking a particular form, it will be understood that the various parts of my invention may be changed without departing from the 10 spirit thereof, and hence I do not limit myself to the precise construction set forth, but consider that I am at liberty to make such changes and alterations as fairly come within the scope of the appended claims.

Having thus described my invention, what 15 I claim as new and desire to secure by Letters Patent is:—

1. The combination of a member having a helically twisted portion and other portions 20 out of axial alignment with said twisted portion; a diaphragm case; a stylus bar; and means for securing said second mentioned portions of said member respectively to the diaphragm case and stylus bar; substantially 25 is described.

2. A device for securing a stylus bar to a sound box, including a member having a helically twisted portion and other portions for respective connection with the stylus bar 30 and a part of the sound box; and a core member positioned within and in engagement with the convolutions of said helically twisted portion of the member; substantially 50 as described.

3. The combination of a member including helically twisted portions spaced apart and connected by a flat portion, said member having other flat portions formed therein, the arrangement being such that said helically twisted portions are respectively between said latter flat portions and said first flat portion; a diaphragm case having flat surface portions; a stylus bar having a flat surface portion; means for securing said 40 second flat portions of the member in coinciding engagement with said flat surface

portions of the case; and means for securing said first mentioned flat surface of the member to the flat surface portion of the stylus bar; substantially as described. 50

4. The combination of a member including helically twisted portions spaced apart and connected by a flat portion, said member having other flat portions formed therein, the arrangement being such that said helically twisted portions are respectively between said latter flat portions and said first flat portion; a diaphragm case having flat surface portions; a stylus bar having a flat surface portion; means for securing said second flat portions of the member in coinciding engagement with said flat surface portions of the case; and means for securing said first mentioned flat surface of the member to the flat surface portion of the stylus bar, said flat portions of said member all being normally included in the same plane; substantially as described. 60

5. The combination of a member having a helically twisted portion and other portions 70 between which said twisted portion is located, said other portions being out of alignment with the helical curvature of said twisted portion; a diaphragm case; a stylus bar; and means for securing said second mentioned portions respectively to said case and stylus bar; substantially as described. 75

6. The combination of a diaphragm case; a stylus bar and a member having a helically twisted part and other portions; and means 80 for insuring the securing of said latter portions of the member to the case and bar in a definite predetermined position; substantially as described.

In testimony whereof I have signed my 85 name to this specification in the presence of two subscribing witnesses.

HARRY J. DURBOROW
